UNITED STATES PATENT OFFICE.

MARCUS H. DAVIS AND SAMUEL R. ATWELL, OF WINCHESTER, VIRGINIA.

DESIGN FOR A BACK FOR PLAYING-CARDS.

SPECIFICATION forming part of Design No. 36,580, dated October 6, 1903.

Application filed August 7, 1903. Serial No. 168,548. Term of patent 7 years.

To all whom it may concern:

Be it known that we, MARCUS H. DAVIS and SAMUEL R. ATWELL, citizens of the United States, residing at Winchester, in the county of Frederick and State of Virginia, have invented a new, original, and ornamental Design for the Backs of Playing-Cards, of which the following is a specification, reference being had to the accompanying drawing, which shows the design in plan view.

What we claim as our invention, and desire to secure by Letters Patent, is—

The ornamental design for the back of a playing-card as shown.

MARCUS H. DAVIS.
SAMUEL R. ATWELL.
